UNITED STATES PATENT OFFICE.

JAMES ALBERT FARMER, OF SOUTH NEW MARKET, NEW HAMPSHIRE.

SPINNING-SPINDLE AND SUPPORT THEREFOR.

SPECIFICATION forming part of Letters Patent No. 377,426, dated February 7, 1888.

Application filed April 1, 1887. Serial No. 233,233. (No model.)

To all whom it may concern:

Be it known that I, JAMES ALBERT FARMER, of South New Market, in the county of Rockingham and State of New Hampshire, have invented certain new and useful Improvements in Spinning-Spindles and Supports Therefor; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to a special construction, which will fully appear from the description and claims.

In the drawings, Figure 1 is an elevation of the spindle and its supporting devices complete, with the bobbin in place on the spindle; Fig. 2, a vertical section of the same, showing the spindle in elevation.

The supporting-case A, which by its construction serves also as a bolster, having top and bottom bearings for the spindle B, is made as follows:

Within a tubular bore, c, of substantially uniform diameter, made in this supporting-case A, but not extending clear through its lower end, is secured at its bottom a bottom bearing, d, made of composition metal of the kind usually employed for spindle-bearings in spinning-machines, to receive the tip of the spindle and serve as its step-bearing, and within the same bore at its top is fixedly secured a tubular top bearing, e—say of about an inch in length—made of composition metal, and adapted to snugly receive and support the spindle at that point, while permitting its free revolution by means of its whirl f. This top bearing, e, projects above the bore c, and has around such projecting end an annular oil space or chamber, g, between the part e and an upward projection, h, on the supporting-case, this part h having at its top an annular rim, i, as shown.

The shoulder j, which may rest on the rail of the spinning-machine, has a shallow groove, k, on its upper face, and from this groove one or more small oil ducts or passages, l, incline downward and lead into the annular space or chamber g. Other oil passages or ducts, m,

are made through the composition tube or top bearing, e, thus carrying the oil into direct contact with the spindle and the inner surface of this bearing, and allowing it in any desired quantity to pass into or to fill the large oil-chamber n between the two bearings d and e, and also to lubricate the step-bearing d. The whirl f is made with a cavity, o, on its under side to receive the rim i, and a small screw, p, in the ring p' of this cavity serves to fasten the spindle down into its step, but yet leave the same free to revolve, this screw projecting beneath the rim. This rim is of such height relatively to the depth of the cavity o that when the spindle is in place in its step-bearing d the top of the rim does not come in contact with the bottom of the cavity; hence needless friction from any such cause is avoided.

I prefer to put a nut, q, on the step, as shown, for the purpose of fastening the supporting-case into the frame, so as to permit of its being adapted for and secured to rails of different sizes or thickness. The turning of this nut in either direction, as may be needed, serves to adapt the supporting-case A to rails of different thicknesses.

It will now be seen that even when the spindle is in place or is running, oil can be poured into the groove k, and which, passing through the ducts l, will first enter the annular chamber 80 or space g, and thence, by the ducts m, enter between the fixed top bearing, e, and the spindle, and thence flow down into the spacious chamber n, and thence to the cavity o' in the step-bearing d.

It will also be seen that a plentiful supply of oil can be poured in, which will last a long time, as there is no chance of leakage or escape at the bottom of the case, because such bottom is integral and has no joint and no outlet, and that the centrifugal action cannot throw out or waste the oil at the top, because any such tendency would merely carry the oil through the ducts m into the annular space g, the bottom of which is lower than the annular groove k.

It will also be seen that the screw p holds the spindle in its proper relation to the step and its bearings and prevents any accidental rising or displacement of the spindle, while it permits its ready removal at any time.

The upper bearing, *e*, being welded or permanently fixed to the supporting-case, cannot shift its position, and therefore cannot in anywise affect or alter the true vertical alignment 5 and proper working of the spindle if the supporting-case itself be placed correctly. The advantages of employing composition metal for this upper bearing, as well as for the lower bearing, will be readily understood by those 10 versed in the art.

My combined bearing performs the duty both of a step and of a bolster, avoiding the disadvantages of having them separate, and also affording a cheap and efficient construction.

15 The spindle below its whirl has a very gentle downward taper, so that when any wear takes place at its bearings, if the spindle in consequence lowers a trifle, this wear is automatically adjusted or compensated for.

20 I claim—

1. The supporting-case described, having

the fixed tubular top bearing, *e*, as described, the rimmed portion *h i*, the annular chamber *g* between the parts *e* and *h*, the groove *k*, ducts *l* and *m*, oil-chamber *n*, and the step-bearing *d*, all substantially as set forth. 25

2. In combination with the supporting-case *A*, having the top and bottom bearings, *e d*, chamber *g*, rim *h i*, groove *k*, ducts *l m*, and oil-chamber *n*, as set forth, the spindle 30 provided with the whirl and screw *p*, as and for the purposes set forth.

3. The case *A*, having its lower and closed end made integral with the body of the case and its top and bottom bearings, *e d*, inserted 35 therein from the top, and provided with chambers *g n*, rim *h i*, ducts *l m*, and groove *k*, all as and for the purposes set forth.

JAMES ALBERT FARMER.
